(57) **CLAIM**

(21) Appl. No.: **29/214,825**

The ornamental design for a battery powered rechargeable sealed beam spotlight, as shown and described.

(22) Filed: **Oct. 8, 2004**

DESCRIPTION

(51) LOC (8) Cl. **26-02**

FIG. 1 is a right side view of a battery powered rechargeable sealed beam spotlight constructed in accordance with the present invention;

(52) U.S. Cl. **D26/45**

FIG. 2 is a front view of a battery powered rechargeable sealed beam spotlight as shown in FIG. 1;

(58) Field of Search D26/37-50; 362/157,
362/158, 171-174, 183-208

FIG. 3 is a left side view of a battery powered rechargeable sealed beam spotlight as shown in FIG. 1;

(56) **References Cited**

FIG. 4 is a top view of a battery powered rechargeable sealed beam spotlight as shown in FIG. 1; and,

U.S. PATENT DOCUMENTS

FIG. 5 is a rear view of a battery powered rechargeable sealed beam spotlight as shown in FIG. 1.
